[57] CLAIM

The ornamental design for an engine heating unit, as shown and described.

DESCRIPTION

FIG. 1 is a perspective view of an engine heating unit showing our new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a bottom plan view thereof.

The broken line showing of environment is for illustrative purposes only and forms no part of the claimed design.

FIG. 1

FIG. 4

FIG. 5

FIG. 6
